UNITED STATES PATENT OFFICE.

ARTHUR B. FAULKNER, OF WILLIAMSPORT, PENNSYLVANIA.

ADJUSTABLE VISE WRENCH.

Application filed December 19, 1923. Serial No. 681,620.

To all whom it may concern:

Be it known that I, ARTHUR B. FAULKNER, a citizen of the United States, residing at Williamsport, in the county of Lycoming and State of Pennsylvania, have invented 5 certain new and useful Improvements in Adjustable Vise Wrenches; and I do hereby declare the following to be a full, clear, and exact description of the invention, such as 10 will enable others skilled in the art to which it appertains to make and use the same.

This invention relates to wrenches of the type generally known as adjustable wrenches.

15 It is well known that in using such wrenches as heretofore ordinarily constructed the jaws are liable to slip and become disengaged from a nut or other article clamped between the jaws by the usual clamping means, thus causing much trouble and annoyance in accomplishing the desired result.

20 The objects of my invention are to overcome these objections and provide a simple, efficient and durable wrench having in addition to the means ordinarily employed for adjusting the movable jaw so as to bring the jaws together and clamp a nut or other article between the jaws, simple, efficient and reliable means acting independently of the 25 usual adjusting means so as to easily and quickly tighten the grip of the jaws upon the nut or other article and prevent the jaws from slipping off or becoming disengaged until released by said gripping means.

30 A further object is to provide a wrench of the character referred to with clamping means operable with one hand and adapted to exert a powerful force with little expenditure of energy in order to fasten the grip of the jaws upon a nut or other article, and to adapt the clamping means to easily and quickly automatically release the grip of the jaws and permit the removal of the wrench without the annoyance and trouble that is 35 often experienced in using ordinary adjustable wrenches.

40 The invention will first be hereinafter more particularly described, with reference to the accompanying drawings, which are to be taken as a part of this specification, and then pointed out in the claims at the end of the description.

45 In said drawings, Fig. 1 is a side view of

an adjustable vise wrench embodying my invention;

55 Fig. 2 is an edge or back view of the same;

60 Fig. 3 is a longitudinal sectional view of a modified form of the device designed for a small wrench with thin jaws;

65 Fig. 4 is a fragmentary detail perspective view of the jaws of the wrench shown in Fig. 3;

70 Fig. 5 is a longitudinal sectional view of a device of the form shown in Fig. 1 showing the main handle member integral with the shank;

75 Fig. 6 is a detail sectional view taken on the line 2—2 of Fig. 4, looking in the direction of the arrows; and

80 Fig. 7 is a fragmentary detail view showing jaws having their confronting surfaces serrated or provided with fine teeth, similar to a Stillson wrench, for use as a pipe wrench.

85 Referring to said drawings, in which the same reference characters are used to denote corresponding parts in different views, the letters A and A¹ denote the jaws of an ordinary adjustable wrench, the jaw A¹ being slidably secured on the shank a of the relatively fixed jaw A, and B denotes the usual adjusting device or screw for bringing the jaws together; said screw being provided with an enlarged peripherally roughened head b for turning it to adjust the movable jaw in the usual way. The shank a has rigidly secured thereto, as shown in Figs. 1 and 2, or formed integrally therewith, as shown in Fig. 5, a handle member 90 C which is preferably substantially semi-circular or trough-shaped in form and provided on the inner side thereof with an apertured or bifurcated lug or projection c, near the base of the handle or its junction with the shank, to form an abutment for one end of a spring D, the other end of which abuts against a nut d screwed on the free end of a rod d¹ carrying the spring; said rod passing through the lug c so as to adapt the 100 spring to exert a force tending to pull the rod toward said lug. The rod d¹ is pivoted at its inner end to a rod or bar E, which is preferably U-shaped or in the form of a yoke, the arms of which embrace a cross-piece F, and are secured at their free ends

to a bearing member G slidably mounted in an opening through the inner end or base of the rigid handle member C and having a socket therein to receive a pintle or stud 5 g on the rear end of the screw B, so as to provide a bearing for the screw at that end, the other end of the screw being inserted in an interiorly threaded socket in the part a^1 of the movable jaw as usual in adjustable 10 wrenches. One end of the crosspiece F is inserted in a slot or hole in the handle member C, so as to provide a fulcrum on which it may rock or tilt; the other end f^1 thereof being arranged to engage a shoulder formed 15 in a recessed end portion of an auxiliary handle member C^1 , which is pivotally mounted beside the handle member C and may be solid, though preferably trough-like 20 in form, for lightness.

20 The cross-piece F is preferably recessed between its two arms to provide a seat for the pointed end of the bearing member G on which it may rock or tilt in a forward direction under pressure of the auxiliary 25 handle member or the recoil of the spring which tends to hold the cross-piece in the position shown in Fig. 5 and through it held the auxiliary handle member normally in the inclined position also shown in Fig. 5.

30 The head b of the screw B is held in a relatively fixed position, to prevent movement thereof in the direction of the axis of the screw, while permitting free rotary movement, by means of a slidable bracket H having 35 its end bent toward the screw so as to straddle the head b with one end fitting in a groove in the bearing member G and the other end overlapping the head and resting upon a flange or shouldered portion thereof 40 so that longitudinal movement of the screw independently of the bracket is prevented while rotary movement thereof is permitted, for adjusting the movable jaw forward and back along the shank of the fixed jaw A.

45 In the modification shown in Fig. 3, which is designed for a small wrench with thin jaws, a rack-bar I is used to take the place of the adjusting screw shown in Figs. 1 and 5, and the bearing member shown in the last 50 mentioned figures is omitted and in place thereof the rear end of the rack is formed with an enlarged and pointed end which seats against the tilting cross-piece in the manner and for the purpose described with 55 reference to Figs. 1 and 5. In said modification the movable jaw is adjusted forward and back by means of a worm gear K which travels therewith, said gear being revolubly mounted in a socket formed in the base portion 60 of the movable jaw, and a slight forward and back movement of the movable jaw independently of the worm gear and rack adjustment for tightening the grip of the jaws on a nut or other article held between the jaws, is accomplished by pressing 65

the auxiliary handle member toward the rigid handle member in the manner hereinbefore described.

In Fig. 7 jaws are shown having fine teeth or serrations on their working faces to adapt 70 the device for use as a pipe wrench.

The utility and advantages of my improvement over wrenches as heretofore ordinarily constructed are obvious. The co-acting pivoted handle member and associated 75 parts provide a compound lever movement by which the user is enabled with one hand to easily and quickly tighten the grip of the jaws on a nut or other article, after it has been clamped between the jaws by manipulating the ordinary adjusting devices with the other hand, and with such power that it becomes practically impossible for the jaws to release their hold until the gripping device is released, this being accomplished 80 quickly and automatically by the recoil of the spring, which retracts the movable jaw and simultaneously restores the lever member of the handle to normal position the instant the pressure thereon is removed. 85

In the form shown the slot or hole in the handle member C, in which one end of the cross-piece or lever F is inserted and has its fulcrum or bearing at that end, is directly opposite a shoulder c^1 on the other handle member C^1 , on which the free end of said cross-piece has a bearing, and the bottom of the recess in said cross-piece forming a seat for the pointed end of the sliding bearing member G, at the opposite side of said bearing points, is arranged directly in line with the two bearing points first mentioned, or in other words, there are two points of bearing on the back of said cross-piece and an intermediate one on the front, all arranged directly in the same line, which arrangement is preferred, as it prevents any sliding motion. 95

100 It will be understood of course that various changes may be made in the details of construction and arrangement of parts without departing from the spirit and scope of my invention.

105 Having thus described my invention, what I claim as new and desire to secure by Letters-Patent of the United States is:—

110 1. An adjustable vise wrench comprising in combination with an ordinary wrench having jaws and associated adjusting devices for bringing said jaws together, means 115 for tightening the grip of the jaws consisting of a main handle member rigid with the shank of the wrench and an auxiliary handle member pivoted at one end beside and at an angle to said main handle member, and spring-actuated means and connections 120 between the same and said adjusting devices tending to separate the jaws, said spring-actuated means and connections being arranged in the line of the longitudinal axis 125 130

- of said main handle member parallel with said shank and including a tilting element interposed in said connections and movable therewith in engagement with said pivoted handle member, for holding the latter normally in its inclined position under tension of the spring; said pivoted handle member being adapted when pressed toward the rigid member to move said element in opposition to the action of the spring, so as to tighten the grip of the jaws, and said spring being adapted to separate the jaws and restore said element and pivoted handle member to normal position when the pressure on the latter is released. 70
2. An adjustable vise wrench comprising in combination with an ordinary wrench having jaws and associated adjusting devices for bringing said jaws together, means for tightening the grip of the jaws consisting of a main handle member rigid with the shank of the wrench and an auxiliary handle member pivoted at one end beside and at an angle to said main handle member, and spring-actuated means and connections between the same and said adjusting devices tending to separate the jaws, said spring-actuated means including a tilting element interposed in said connections and movable therewith, having one end fulcrumed on said rigid handle member and the other end engaging said pivoted handle member, for holding the latter normally in its inclined position under tension of the spring; said pivoted handle member being adapted when pressed toward the rigid member to move said element in opposition to the action of the spring so as to tighten the grip of the jaws, and said spring being adapted to separate the jaws and restore said element and pivoted handle member to normal position when the pressure on the latter is released. 80
3. An adjustable vise wrench comprising in combination with an ordinary wrench having jaws and associated adjusting devices for bringing said jaws together, a main handle member rigid with the shank of the wrench and an auxiliary handle member pivoted at one end beside and at an angle to said main handle member, and spring-actuated means and connections between the same and said adjusting means tending to separate said jaws; said spring-actuated means including a tilting cross-piece interposed in the connections between said spring and adjusting means with one end inserted in a hole in said rigid handle and the other end engaging the pivoted handle member so as to adapt the spring to hold the latter member normally in an inclined position, the latter handle member being adapted when pressed toward the rigid member to move said cross-piece on its fulcrum in opposition to the action of the spring and tighten the grip of the jaws, and said spring being adapted to separate the jaws and restore said cross-piece and pivoted handle member to normal position when the pressure on the latter is released. 85
4. An adjustable vise wrench comprising a relatively fixed jaw having a shank connecting it with a handle, and a movable jaw slidably secured on said shank; said handle having a main portion rigid with said shank and offset therefrom, and an auxiliary handle member pivotally secured to said shank in the line of its longitudinal axis, means for adjusting said movable jaw along said shank, and spring-actuated means carried by said main portion of the handle in the line of its longitudinal axis tending to retract said movable jaw and hold said auxiliary handle member normally at an angle to said main portion and also co-acting with said auxiliary handle member after an article has been gripped between the jaws by the action of said adjusting means to impart a slight forward movement to said movable jaw when said auxiliary handle member is forced toward said main handle portion. 90
5. An adjustable vise wrench comprising a relatively fixed jaw having a shank connecting it with a handle, and a movable jaw slidably secured on said shank; said handle having a main portion rigid with said shank and offset therefrom and an auxiliary handle member pivotally secured at the junction of said shank with said main portion of the handle in line with the longitudinal axis of the shank, means for adjusting said movable jaw along said shank, and spring-actuated means connecting said adjusting means with said main portion of the handle for holding said auxiliary handle member normally at an angle to said main portion; said spring-actuated means including a tilting element having a bearing on said auxiliary handle member, whereby after an article has been gripped between the jaws by the action of said adjusting means a slight forward movement may be imparted to said movable jaw to tighten the grip on said article by forcing said auxiliary handle member toward said main handle portion; said spring-actuated means being adapted to retract said movable jaw and restore said auxiliary member to normal position when the auxiliary member is released. 100
6. An adjustable vise wrench comprising a relatively fixed jaw having a shank connecting it with a handle, and a movable jaw slidably secured on said shank; said handle having a main portion rigid with said shank and offset therefrom, and an auxiliary member pivotally mounted thereon at one end in the line of the longitudinal axis of said shank, means arranged in the line of said offset handle portion for adjusting said movable jaw along said shank, and 110
- 120
- 125
- 130

- spring-actuated means arranged in the line of said adjusting means for holding said auxiliary handle member normally at an angle to said main portion; said spring-actuated means co-acting with said auxiliary handle member to impart a slight forward movement to said movable jaw when said auxiliary handle member is forced toward said main handle portion and to retract said movable jaw and restore said auxiliary member to normal position when the latter member is released.
7. An adjustable vise wrench comprising a relatively fixed jaw having a shank connecting it with a handle, and a movable jaw slidably secured on said shank; said handle having a main portion rigid with said shank and offset therefrom and an auxiliary handle member fulcrumed at one end in line with said shank, means for adjusting said movable jaw along said shank, spring-actuated means and connections between the same and said adjusting means tending to separate said jaws and hold said handle members apart and adapted to co-operate with said auxiliary handle member to impart a slight forward movement to said movable jaw when said auxiliary handle member is forced toward said main portion; said spring-actuated means being adapted to retract said movable jaw and force said handle members apart when said auxiliary handle member is released.
8. A wrench having jaws and associated adjusting devices for bringing said jaws together, and a vise attachment for tightening the grip of the jaws, said attachment comprising a main handle member rigid with the shank of the wrench and an auxiliary handle member pivoted at one end beside said main handle member at an angle thereto, and spring-actuated means and connections between the same and said adjusting means tending to separate said jaws, said spring-actuated means including a cross-piece interposed in said connections with one end engaging the pivoted handle member, and the other end fulcrumed on said rigid handle member, said pivoted handle member being adapted when pressed toward the rigid member to move said cross-piece and adjusting devices in opposition to the action of the spring and tighten the grip of the jaws, and said spring being adapted to separate the jaws when the pressure on said auxiliary handle member is released.
9. In a wrench, in combination with a relatively fixed jaw having a shank connecting it with a handle member rigid with said shank and a movable jaw slidably along said shank together with adjusting devices for bringing the jaws together, a compound lever movement for tightening the grip of the jaws after an article has been initially gripped therebetween; said lever movement

comprising a spring tending to retract said movable jaw and connections between said spring and said adjusting devices tending to separate the jaws, a rocking element interposed in said connections and a pivoted handle member serving as a lever acting upon said rocking element to force the jaws together in opposition to the action of the spring.

10. An adjustable vise wrench comprising a relatively fixed and a movable jaw; said fixed jaw having a shank connecting it with a handle member rigid therewith, and said movable jaw slidably secured on said shank, an auxiliary handle member pivoted at one end beside and extending at an angle to said rigid handle member, a rotary device for adjusting said movable jaw along said shank with provision to permit a slight longitudinal movement of said device with said movable jaw, yieldable means connecting said rigid handle member with said rotary device and tending to separate the jaws, the latter means including a tilting element on which said auxiliary handle member acts as a lever to move said movable jaw toward said fixed jaw when said auxiliary handle member is pressed toward the fixed member, said yieldable means being adapted to separate the jaws when the pressure on said auxiliary handle member is removed.

11. In a wrench, in combination with adjusting devices for bringing the jaws together, a compound lever movement for tightening the grip of the jaws comprising a spring and connections between the same and said adjusting devices tending to separate the jaws, a rocking element interposed in said connections and a handle member serving as a lever acting upon said rocking element to force the jaws together in opposition to the action of the spring; said rocking element consisting of a cross-piece or lever located between said spring-actuated means and said movable jaw-adjusting means, and having on one side, at opposite ends thereof, two bearing points, and on the other side an intermediate bearing point engaging a member of said adjusting means; said bearing points being all arranged directly in the same line.

12. An adjustable vise wrench comprising a main handle member rigid with the shank of a relatively fixed jaw, a movable jaw slidably supported on said shank, means for adjusting said jaws so as to grip an article therebetween, an auxiliary handle member pivotally secured at one end beside said main handle member in the line of the longitudinal axis of said shank, and spring-actuated means connecting said adjusting means with said main handle member for retracting said movable jaw, said connecting means including an element having a bearing on said main and auxiliary handle mem-

bers, whereby pressure on the latter member will tighten the grip of the jaws on an article after it has been gripped by the action of said adjusting means.

- 5 13. A vise wrench comprising in combination a relatively fixed jaw having a shank connecting it with a rigid handle member, a movable jaw slidable along said shank, a screw for adjusting said movable jaw, an auxiliary handle member pivoted at one end in the line of said shank, and means for tightening the grip of said jaws after an article has been gripped therebetween by actuating said screw; said means comprising
10 a rod slidably mounted on said rigid handle member, a spring on said rod abutting at one end against a fixture on said rigid handle member through which said

rod protrudes and at the other end against a nut or collar fixed on said rod, the latter 20 having one end pivoted to a slideable rod or bar having yoke-arms between which is placed a tilting element fulcrumed at one end on said rigid handle member and at the other end on said pivoted handle member, 25 and a bearing member between said tilting element and said screw slidably fitted upon said rigid handle member and having a pointed end bearing against said tilting element intermediate its length and having a 30 socket in the other end thereof in which is fitted a stud projecting from the adjacent end of said screw.

In testimony whereof I affix my signature.

ARTHUR B. FAULKNER.
